UNITED STATES PATENT OFFICE.

SYLVENUS PENNELL, OF GIRARD, OHIO.

DESIGN FOR A PUMP-FROG.

SPECIFICATION forming part of Design No. 27,951, dated December 7, 1897.

Application filed August 18, 1897. Serial No. 648,654. Term of patent 14 years.

To all whom it may concern.

Be it known that I, SYLVENUS PENNELL, a citizen of the United States, residing at Girard, in the county of Trumbull and State of Ohio, have invented a certain new and original Design for a Frog for Pumps, of which the following is a specification, reference being had therein to the accompanying drawings.

My invention relates to a design for a frog or switchway for pipes to be used in a double-action force-pump, and to all intents and purposes is a single casting of metal having the form and configuration duly shown in the accompanying drawings, in which—

Figure 1 represents a view of the invention in elevation, and Fig. 2 a sectional view upon a longitudinal mid-line.

The leading feature of my design consists

in the parallel twin pipes 2, one of which entering the other forms a single pipe 1, the 20 twin pipes, however, being adjacent to each other throughout their entire length.

1 is the single pipe, with twin branches 2 lying close to each other and parallel throughout their length. 3 and 4 are exterior screw-threadings, and 5 and 6 are internal screw-threadings.

What I claim is—

The design for a pump-frog herein shown and described.

In testimony whereof I affix my signature in presence of two witnesses.

SYLVENUS PENNELL.

Witnesses:

HORACE T. SMITH,
C. R. TRUESDALE.
